CLAIM

The ornamental design for a basket battery as shown and described.

DESCRIPTION

FIG. 1 is a front perspective view of a basket battery showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is rear perspective view thereof.

The broken lines in the drawing are for illustrative purposes only and forming no part of the claimed design.

1 Claim, 6 Drawing Sheets
